FIG. 2

Technical drawing of a mechanical assembly, showing various components and their numbers. The drawing includes a main assembly with a central vertical rod, a side view of a cylinder, and a detailed view of a valve mechanism. Components are numbered 22 through 77, 83, 103, and 114. Labels A, A', and IV are present, along with force vector F.

MACHINE FOR AUTOMATICALLY SETTING
AND TRUING THE ENDS OF THE TEETH
OF SAWS

André Vigneau, Norrois, France

Application January 8, 1946, Serial No. 639,762
In France December 27, 1944

20 Claims. (Cl. 76—54)

1

It is known that for giving clearance to band saws (or other like saws) it is customary to set, that is to say to spread, in the transverse direction, the end of the saw teeth, and then to true them, that is to say, to calibrate this spreading of the teeth in such a manner that all the teeth give, owing to their substantially identical shape, a uniform clearance for the blade to pass.

The set is generally effected by means of an eccentric (a cam-like pivoting tool of special shape) which engages the underside (front part of the end) of the tooth of which the back bears on a small anvil.

Hitherto, the setting apparatus was moved, either by hand, tooth by tooth, along the stationary blade, or was given a reciprocating motion of retraction (in automatic machines) in order to enable the movable saw blade to be fed forwards.

Whatever may be the type of apparatus (manually or automatically operated) the same difficulty is encountered, which is the application of a considerable force (for setting the teeth) to a movable machine member, in this case the setting tool.

The object of the present invention is the new industrial product which is formed by a machine for setting and truing (calibrating) automatically the ends of the teeth of band saws (and other like saws), said machine, which obviates the drawback referred to above, having, amongst other peculiarities, that of comprising, on the one hand a fixed setting apparatus in which automatically engage, one by one and with a reciprocating movement, the teeth of the saw of which the blade moves forward automatically at each cycle of operation and, on the other hand a truing device which can move in the longitudinal and vertical directions so as to place itself in the correct position relatively to the tooth to be trued, so that small differences in the set of the saw teeth or inaccuracies of adjustment are compensated.

Means are provided for automatically bringing the blade (preferably with an arcuate motion) into the correct position, so that the tooth to be set comes into the exact position (vertically and longitudinally) between the setting cam and the anvil.

Means are furthermore provided for automatically obtaining from a single control the forward feeding of the saw blade, its (arcuate) upward and downward movements, the setting and the truing of the teeth.

The various characteristics of the novel ma-

chine will become apparent from the ensuing description which relates to a constructional example shown diagrammatically and nonlimitatively in the accompanying drawing in which:

Fig. 1 is a plan view of the machine;

Fig. 2 is a vertical section thereof along the line II—II (axis of the saw blade) of Fig. 1;

Fig. 3 is a vertical section, substantially along the line III—III of Fig. 1, of the setting device;

Fig. 4 is a vertical section, substantially along the line IV—IV of Fig. 1 of the truing (calibrating) device;

Fig. 5 is a partial vertical section of the machine along the line V—V of Fig. 1;

Fig. 6 is a similar view to Fig. 5, the members shown being however in another position;

Figs. 7, 8 and 9 are respectively sections taken along the lines VII—VII, VIII—VIII and IX—IX of Fig. 1, the object of these sections being simply to show the respective positions of the various actuating members of the machine;

Figs. 10 and 11 show two different positions of the locking fingers of a group of actuating members of the machine;

Finally, Fig. 12 is a perspective view of a portion of a saw blade, one part of the teeth of which are of normal shape, whereas another part of the teeth has been subjected to the setting and truing or calibrating operations.

As can be seen in this latter figure, the result to be obtained is the setting and, consequently, the transverse and suitably trued spreading of the end of the teeth of a saw, the blade of which is designated by A, the normal teeth by B and the teeth which have been set and trued by C.

The machine which can do the work referred to above and which is shown in Figs. 1 to 11, comprises a blade-holder 1, which is adapted to move on guides 2 which are secured to the frame 3 of the machine and which support the saw blade A whose movements are braked by two vertically adjustable leaf springs 4, the pressure of which can be adjusted by means of screws controlled by knurled knobs 5.

The blade-holder 1, which is adjustable in the vertical direction (in order to enable it to be adapted to different widths of blades), is mounted on an adjusting screw 6 controlled by a knob 7 and engaged in two stub-shafts 8 and 9 which are journaled respectively in cranks 10 and 11, so that an articulated parallelogram a—b—c—d is obtained.

In the inoperative position of the blade-holder 55 (low position shown in Fig. 2), the lower end

of the screw 6 rests on an adjustable stop 12 fitted on the frame 1.

The shaft 9 of the upper crank 11, which is the actuating crank fixed on an actuating shaft 13, enables the smooth upper portion of the screw 6 to slide, the control of said screw 6, which is effected through the intermediary of a spring 14, being consequently resilient so as to compensate a possible defect in the positioning of the tooth to be set.

The rocking of the upper crank 11 and, consequently, of the lower crank 10 (in an anti-clockwise direction) causes the blade-holder 1 to move in such a manner that, for the setting and truing operations, the blade takes up the position designated by A' in the drawing.

Before the upward movement of the blade A takes place, said blade is moved one tooth in the direction of the arrow F, by means of a finger 15 carried by a pusher 16 adjustably pivoted at 17 on a lever 18 fixed on a driving shaft 19 journalled in the frame of the machine, and actuated in the manner which will be described hereinafter. Said pusher feeds the tooth which is to be set (and not the preceding tooth), this being so that the differences of spacing of the teeth do not affect the engagement of the tooth in the setting device.

The useful travel (forward feeding of the blade) at each cycle of the machine is obtained, as a function of the pitch of the teeth of the saw, by an appropriate adjustment of the return travel of the lever 18. This return travel is defined by means of an adjustable stop screw 20.

The setting device (Figs. 1, 2 and 3) comprises a setting device body 21 having therein a slit 22 for the saw blade to pass, its being possible to adjust the angular position of said body in a support 23 secured to the frame of the machine and to lock said body in said support by means of a screw 24. In the body 21 is mounted an adjustable anvil 25 intended to support the back of the tooth during the setting operation. The tooth subjected to the setting operation is held stationary in the transverse direction (the blade A having previously been brought into the position A') by means of a fixed but adjustable die-plate 26 and of a die 27 adjustably engaged in a stub-shaft 28 journalled in the body 21 and carrying a special helical slope 29. In the body 21 is also mounted an adjustable clutch member 30 which is locked therein by means of a screw 31. Said clutch member carries a special slope which corresponds to the slope 29 of the stub-shaft 28, and which imparts a very rapid movement to the stub-shaft in question during a fraction of its revolution, then a slow but powerful movement during the complement of its rotation. A retracting spring 32 ensures the contact between the slopes of the two members 28 and 30. The rotation of the stub-shaft 28 is effected by means of a lever 33, the control of which is obtained by a mechanism which will be referred to hereinafter.

When the lever 33 swings (Fig. 2) in a clockwise direction, the action of the slope 29 effects the transverse clamping of the tooth to be set between the fixed die-plate 26 and the die 27 which is pushed towards the latter owing to the axial movement of the shaft 28.

The setting proper of the tooth is obtained by means of a kind of cam 34 (Figs. 2 and 9) having two cylindrical portions journalled in the two parts of the body 21 which are separated by the slit 22 and merges into the front where it ter-

minates in a hexagon on which is fitted an actuating lever which will be referred to hereinafter. The swinging of the cam 34 in a clockwise direction produces the setting of a tooth at each cycle of the machine.

The truing (or calibration) of the teeth which have been set, in the device just described, is produced by the pressing of the tooth between two conical shaped dies. For the truing to be accurate, it is necessary that the end of the tooth should always be located in the same position in the die.

In the machine which is the object of the invention, as the truing apparatus does not calibrate the tooth which is being set but one of the subsequent teeth, account has to be taken of the possible differences of spacing and of height which may occur in the teeth of saws, and also of the play or of the bending of the blade-support 1.

According to the invention, means are provided so that the tooth to be trued is always accurately lodged in the truing dies.

The truing device comprises a truing device body 35 pivotally mounted at 36 on a support 37 adapted to slide on a horizontal guide 38 secured to the frame. In the inoperative position, the body 35 rests on a stop screw 39 fixed to the support 37. In the body 35 is a set of dies 40 and of die-plates 41, which can be adjusted angularly by means of a finger 42 and which are connected to each other by means of sliding assembly fingers 43, 43' and 43'', this being so that they can move away from or towards each other angularly. A stop plate 44 holds the die-plate in the appropriate position. A screw 44' enables the position of the blade A to be exactly adjusted in the transverse direction.

At its rear end, the die 40 has a housing which is closed by an assembly plate 45 and in which penetrates the head 46 of a screw 47 which is adjustable in a stub-shaft 48 on which is fixed the control lever 49 which is actuated by a connecting rod 50 provided with an adjusting groove in which can be locked the crank 51 carried by the lever 49, said connecting rod being controlled by means which will be described hereinafter. The stub-shaft 48 is provided with a helical slope 52 with a stop, said slope co-operating with a corresponding slope of an adjustable clutch member 53 clamped in the body 35 by means of a screw 54. A retracting spring 55 ensures permanent contact between the aforesaid slopes. On the arm 49' of the lever 49 is attached one end of a retracting spring 56 of which the other end is attached, through the intermediary of a finger 57, to the body 35 of the truing device.

The body 35 carries, furthermore, a bearing plate 58, the function of which will be apparent hereinafter.

The above described truing device operates in synchronism with the setting device previously described, and in the following manner, its being remembered that the saw teeth located before the truing device (on the left of the truing device in Figs. 1 and 2) have already undergone the setting operation by the setting device which precedes the truing device (in the direction of feed of the blade) and which has been described hereinbefore. It should also be remembered that the body 35 of the truing or calibrating device can effect two movements, viz. a swinging movement about the shaft 36 and a longitudinal movement on the horizontal guide 38.

By means of the adjusting groove provided in

the connecting rod 50, the truing apparatus is so placed that, when the blade A is in the raised position A', the lower assembly finger 43 is retracted from the underside of the tooth a distance of 1 cm. for example.

When the blade takes up the position A', the end of the tooth D lifts, through the instrumentality of the plate 58, the body of the truing device which swings about the shaft 36. The truing device is thus placed in its correct position vertically.

When the connecting rod 50 exerts a thrust (towards the right in Figs. 1 and 2) on the lever 49, said lever, which is first of all held stationary by the spring 56, cannot swing with the stub-shaft 48 in the body 35 and the whole truing device moves towards the right (Figs. 1 and 2) on the slide 37 until the finger 43 abuts against the underside of the tooth to be trued. At this instant, the whole truing device can no longer move towards the right and, as the connecting rod 50 continues to urge the lever 49, said lever overcomes the pull exerted by the spring 56 and swings with the stub-shaft 48. By the action of the slopes, the shaft 48 and, consequently, the screw 47 move towards the right (Fig. 4) and the aforesaid screw pushes the movable truing die 40 towards the die-plate 41. This pressing movement produces the truing of the tooth.

When the connecting rod 50 returns to its starting position, it effects the release or separation of the die 40 and the die-plate 41 until the slope 52 abuts against its stop. At this instant, as the return stroke of the connecting rod 50 is not completed, the end of the return stroke of the connecting rod in question returns the truing apparatus to its starting position (toward the left in Figs. 1 and 2).

The operations of automatic feeding of the saw blade (at the beginning of each cycle of the machine), of raising the blade-support, of setting, of truing of the saw teeth and of lowering the blade (at the end of each cycle) are effected by a single control mechanism.

This mechanism comprises a worm 60 (Fig. 5) fixed on a shaft 61 journalled in two bearings 62 and 63 fixed to the frame 3, one end of said shaft carrying a loose pulley 64 and a fixed pulley 65 on which is mounted a crank handle 66.

The worm 60 meshes with a spiral gear 67 fixed on a shaft 68 journalled in bearings 69 and 70 of the frame 3. The shaft 60 carries (Figs. 1 and 7) a lifting cam 71 associated with a lever 72 carrying a roller 72'. The cam 71 co-operates with a roller 73 carried by a lever 74 fixed on the shaft 13 controlling the parallelogram (a—b—c—d) for lifting the blade-support 1. The roller supporting lever 72 co-operates with a lever 75 fixed on the shaft 19 of the lever 18 controlling the feed of the saw blade. An arm 76, also fixed on the shaft 19, is subjected to the action of a retracting spring 77 attached to the frame 3 of the machine.

It will be seen that at each complete rotation of the shaft 68 (which rotation corresponds to a cycle of operation of the machine), the blade-holder 1 is periodically raised and lowered (through the instrumentality of the members 71, 73, 74, 13, 11, 10, 6). This movement of the blade-holder is synchronised with that of the pusher finger 15 (which is actuated through the members 72, 72', 75, 76, 77, 19, 18, 16).

One of the faces of the spiral gear 67 is provided with a drum 78, the periphery of which

carries an unlocking projection 79 and the free face of which carries a locking roller 80.

The roller 80 co-operates with a locking lever 81 secured to a sleeve 82 adapted to rotate loosely on a shaft 83 which acts as a guide for said sleeve and the use of which will become apparent hereinafter. At one of its ends, the sleeve 82 carries a clevis 84 in which is pivoted an undocking lever 85 provided, on the one hand with a heel 86 intended to co-operate with the unlocking projection 79 of the drum 78 and, on the other hand, with an adjustable stop screw 87, the free end of which co-operates with the smooth periphery of the aforesaid drum 78. At the opposite end, the sleeve 82 is secured to a resilient actuating lever 88 (Figs. 1 and 8) which actuates, through the intermediary of a compression spring 89, an intermediate lever 90 adapted to rotate loosely on the sleeve 82. The intermediate lever 90 is connected to one end of a connecting rod 91, the other end of which is connected to the actuating lever 33 of the setting device.

Before the operations of setting and of truing take place, the blade is clamped in the setting device owing to the swinging (in an anti-clockwise direction) of the lever 81 (by the action of the roller 80) with the sleeve 82, the lever 88 and the intermediate lever 90 and to the translatory movement of the coupling rod 91. After the setting and truing operations, all the members are brought into the unlocking position (Fig. 6) owing to the projection 79 encountering the heel 86, thereby moving back the unlocking lever 85 and swinging the clevis 84 in a clockwise direction. The escapement between the heel 86 (carried by the lever 85) and the projection 79 is adjusted by means of the screw 87 (Fig. 6). The holding of the members in the unlocked position is effected by a finger 92 which is secured to the lever 88 and which co-operates with a leaf-spring 93 fixed to the frame of the machine (Figs. 1, 10 and 11).

The actuation of the setting device and of the truing device is effected by a roller 94 mounted on the spiral gear 67, on the opposite side of the drum 78. Said roller co-operates with an actuating lever 95 fixed by means of a screw 96 on the shaft 83, one end of which carries a finger 97 co-operating with a stop 98 and with a retaining leaf-spring 99 fixed to the frame 3. The lever 95 carries, furthermore, an arm 100 fitted with a stop screw 101 co-operating (during the return movement) with an ear 102 secured to the clevis 84.

One the shaft 83 is fixed a lever 103 (Fig. 1) connected to one end of the connecting rod 50 actuating the truing device.

Finally, at its free end, the shaft 83 carries a clevis-shaped lever 104 in which can slide a clutch pin 105 normally engaging a quadrant 106 of a lever 107 thereby securing said lever 107 to the shaft 83. The lever 107 is pivoted to a slider 108 (Fig. 9) which can be adjusted in the groove 109 of a coupling rod 110 which it controls resiliently. Said coupling rod is connected at 111 to a lever 112 engaged on the hexagon of the setting cam 34. The lever 112 is locked on the cam 34. When the cam portion of the latter is deformed by the work, said cam can move transversely and is held in the chosen position by means of a right angle guide 113 which is fixed to the body of the setting device by means of a screw 114 and is engaged in a groove 115 provided in the body of the lever 112.

It will be appreciated from the drawing that the various transmission and control members are arranged, organized and fixed in such a manner that one complete revolution of the spiral gear 67 (which revolution corresponds to a cycle of operation of the machine) effects the following sequence of operations:

1. (a) The pusher 15 feeds the blade of the saw an amount equal to one saw tooth;
- (b) The pusher returns to its starting point;
2. The blade-support 1 moves upwards and brings the saw from the position A to the position A', during which operation:
  - (a) The tooth to be set is placed between the cam 34 and the anvil 25;
  - (b) The end of the tooth which has already been set and which is located under the truing device 35 lifts same and places it in the correct position vertically;
  3. The clamping mechanism, provided in the setting device 21 clamps, in the transverse direction, the blade which has been brought into the high position;
  4. The cam 34 is actuated and sets the tooth which is supported against the anvil:

Simultaneously, the truing devices 35 (raised to the correct height) moves the guide 38 until the stop 43 of the dies abuts against the tooth to be trued, at which instant the helical slope 52 of the truing device comes into action, thereby causing the tooth to be calibrated between the die 40 and the die-plate 41;

5. After the setting and the truing operations, there simultaneously take place the unlocking in the setting device 21 and (through the intermediary of the members 100-101-102) the unclamping of the truing dies 40-41 and return of the cam 34 to the initial position;

The truing device then returns to its starting position;

6. The blade-support 1 moves down into its initial position, thereby causing:
  - (a) The saw blade to move downwards from the position A' to the position A;
  - (b) The truing device 35 to move downwards and bear against its stop 39.

I claim:

1. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, and means controlled by the tooth to be acted upon by said truing means for adjusting said truing means in the horizontal and vertical planes so that said truing means may be automatically correctly positioned with respect to the tooth to be trued.

2. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, means controlled by the tooth to be acted upon by said truing means for adjusting said truing means in the horizontal and vertical planes so that said truing means may be automatically

correctly positioned with respect to the tooth to be trued, said setting means comprising a body angularly adjustable relative to said frame having a slot therein for the saw blade, an anvil for supporting the saw tooth during the setting thereof, a cam for setting the tooth and means automatically operated for locking the saw blade during the setting of the tooth.

3. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, an abutment located adjacent said setting means, a movable member cooperating with said abutment for locking the saw blade during the setting operation, said movable member having a helical incline thereon, a cooperating helical incline fixed relative to said first named helical incline, and means for rotating said movable element at predetermined periods so that said movable member, due to the cooperating inclines, will cooperate with said abutment to lock said saw blade during the setting operation.

4. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, said truing means being located in a body slidably and pivotally mounted and comprising a fixed die, a movable die cooperating with said fixed die for truing the tooth operated upon, and cam means operable during each operational cycle of the machine for moving said movable die towards said fixed die.

5. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, means for moving said supporting means into and away from the position in which the setting and truing operations are performed, said last named means comprising an articulated parallelogram movable at each operational cycle of the machine.

6. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, means for moving said supporting means into and away from the position in which the setting and truing operations are performed, said last named means comprising an articulated parallelogram, an oscillating shaft oscillated at each operational cycle of the machine and means

connecting said oscillating shaft with said articulated parallelogram so that said supporting means for said blade is moved into and away from said setting and truing means.

7. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, means for locking said saw blade during the setting operation, a driving shaft, a worm fixed on said driving shaft, a spiral gear driven by said worm, a drum mounted on one of the faces of said spiral gear, cam means upon said drum controlling the unlocking of said locking means, a roller also mounted on said drum controlling the locking of said locking means, and a second roller mounted upon the other face of said spiral gear controlling said setting means.

8. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, means for locking said saw blade during the setting operation, a driving shaft, a worm fixed on said driving shaft, a spiral gear driven by said worm, a drum mounted on one of the faces of said spiral gear, cam means upon said drum controlling the unlocking of said locking means, a roller also mounted on said drum controlling the locking of said locking means, and a rocking lever operable by said roller controlling the operation of said truing means.

9. A machine for automatically setting and truing the teeth of band saws or the like comprising a frame, setting means mounted on said frame, means for supporting a saw blade, means for feeding said saw blade step by step during each operational cycle of the machine so that the saw teeth are successively acted upon by said setting means, truing means acting upon said teeth after they have been set by said setting means, means for moving said supporting means for said saw blade into and away from said setting means and truing means, a driving shaft, a worm fixed on said driving shaft, a gear driven by said worm, a cam driven by said gear, and means operated by said cam for operating said means for moving said supporting means for said saw blade.

10. A machine for automatically setting and truing the teeth of band saws or the like comprising a frame, setting means mounted on said frame, truing means also mounted upon said frame, means for moving a saw blade into and away from said setting means and said truing means, means for feeding said saw blade step by step during each operational cycle of the machine so that the saw teeth are successively acted upon by said setting means and said truing means, and means for locking said saw blade during the setting and truing operations.

11. A machine for automatically setting and truing the teeth of band saws or the like comprising a frame, setting means mounted on said frame, truing means also mounted upon said

frame, means for moving a saw blade into and away from said setting means and said truing means, means for feeding said saw blade step by step during each operational cycle of the machine so that the saw teeth are successively acted upon by said setting means and said truing means, means for locking said saw blade during the setting and truing operations, and cam means controlling said locking means to actuate the initial movement of said locking means rapidly and the final locking movement at reduced speed.

12. A machine for automatically setting and truing the teeth of band saws or the like comprising a frame, setting means mounted on said frame and fixedly positioned with respect to said frame during operation of the machine, means for supporting a saw blade, means for feeding said saw blade step by step during each operational cycle of the machine so that the saw teeth are successively acted upon by said setting means, truing means acting upon said teeth after they have been set by said setting means, and means controlled by the tooth to be acted upon by said truing means for adjusting said truing means in the horizontal and vertical planes so that said truing means may be automatically correctly positioned with respect to the tooth to be trued.

13. A machine for automatically setting and truing the teeth of band saws or the like comprising a frame, setting means mounted on said frame and fixedly positioned with respect to said frame during operation of the machine, means for supporting a saw blade, means for feeding said saw blade step by step during each operational cycle of the machine so that the saw teeth are successively acted upon by said setting means, truing means acting upon said teeth after they have been set by said setting means, means controlled by the tooth to be acted upon by said truing means for adjusting said truing means in the horizontal and vertical planes so that said truing means may be automatically correctly positioned with respect to the tooth to be trued, said setting means comprising a body angularly adjustable relative to said frame having a slot therein for the saw blade, an anvil for supporting the saw tooth during the setting thereof, a cam for setting the tooth and means automatically operated for locking the saw blade during the setting of the tooth.

14. A machine for automatically setting and truing the teeth of band saws or the like comprising a frame, setting means mounted on said frame and fixedly positioned with respect to said frame during operation of the machine, means for supporting a saw blade, means for feeding said saw blade step by step during each operational cycle of the machine so that the saw teeth are successively acted upon by said setting means, truing means acting upon said teeth after they have been set by said setting means, an abutment located adjacent said setting means, a movable member cooperating with said abutment for locking the saw blade during the setting operation, said movable member having a helical incline thereon, a cooperating helical incline fixed relative to said first named helical incline, and means for rotating said movable element at predetermined periods so that said movable member, due to the cooperating inclines, will cooperate with said abutment to lock said saw blade during the setting operation.

15. A machine for automatically setting and truing the teeth of band saws or the like comprising a frame, setting means mounted on said

frame and fixedly positioned with respect to said frame during operation of the machine, means for supporting a saw blade, means for feeding said saw blade step by step during each operational cycle of the machine so that the saw teeth are successively acted upon by said setting means, truing means acting upon said teeth after they have been set by said setting means, means for moving said supporting means into and away from the position in which the setting and truing operations are performed, said last named means comprising an articulated parallelogram movable at each operational cycle of the machine.

16. A machine for automatically setting the teeth of band saws or the like comprising a frame, setting means mounted on said frame and fixedly positioned with respect to said frame during operation of the machine, means for supporting a saw blade, means for feeding said saw blade step by step during each operational cycle of the machine so that the saw teeth are successively acted upon by said setting means, means for moving said supporting means into and away from the position in which the setting operation is performed, said last named means comprising an articulated parallelogram movable at each operational cycle of the machine.

17. A machine for automatically setting the teeth of band saws or the like comprising a frame, setting means mounted on said frame and fixedly positioned with respect to said frame during operation of the machine, means for supporting a saw blade, means for feeding said saw blade step by step during each operational cycle of the machine so that the saw teeth are successively acted upon by said setting means, means for moving said supporting means into and away from the position in which the setting operation is performed, said last named means comprising an articulated parallelogram, an oscillating shaft oscillated at each operational cycle of the machine and means connecting said oscillating shaft with said articulated parallelogram so that said supporting means for said blade is moved into and away from said setting means.

18. A machine for automatically setting the teeth of band saws or the like comprising a frame, setting means mounted on said frame, means for supporting a saw blade, means for feeding said saw blade step by step during each operational cycle of the machine so that the saw teeth are successively acted upon by said setting means, means for locking said saw blade during the setting operation, a driving shaft, a worm fixed on

said driving shaft, a spiral gear driven by said worm, a drum mounted on one of the faces of said spiral gear, cam means upon said drum controlling the unlocking of said locking means, a roller also mounted on said drum controlling the locking of said locking means, and a second roller mounted upon the other face of said spiral gear controlling said setting means.

19. A machine for automatically setting the teeth of band saws or the like comprising a frame, setting means mounted on said frame and fixedly positioned with respect to said frame during operation of the machine, means for supporting a saw blade, means for feeding said saw blade step by step during each operational cycle of the machine so that the saw teeth are successively acted upon by said setting means, means for moving said supporting means for said saw blade into and away from said setting means, a driving shaft, a worm fixed on said driving shaft, a gear driven by said worm, a cam driven by said gear, and means operated by said cam for operating said means for moving said supporting means for said saw blade.

20. A machine for automatically setting the teeth of band saws or the like comprising a frame, setting means mounted on said frame and fixedly positioned with respect to said frame during operation of the machine, means for moving a saw blade into and away from said setting means, means for feeding said saw blade step by step during each operational cycle of the machine so that the saw teeth are successively acted upon by said setting means, means for locking said saw blade during the setting operation.

ANDRÉ VIGNEAU.

Certificate of Correction

Patent No. 2,528,925

November 7, 1950

ANDRÉ VIGNEAU

It is hereby certified that error appears in the above numbered patent requiring correction as follows:

In the grant, line 15, strike out "of SEVENTEEN years", same line, after "grant" insert *until December 27, 1964*; in the heading to the printed specification, between lines 7 and 8, insert the following: *Section 1, Public Law 690, August 8, 1946. Patent expires December 27, 1964*:

and that the said Letters Patent should be read as corrected above, so that the same may conform to the record of the case in the Patent Office.

Signed and sealed this 4th day of March, A. D. 1952.

[SEAL]

THOMAS F. MURPHY,
Assistant Commissioner of Patents.
